Charles H. Lavis

United States Patent Office.

CHARLES H. LAVIS, OF PHILADELPHIA, PENNSYLVANIA, ASSIGNOR TO
PHILIP FARLEY, OF SAME PLACE.

Letters Patent No. 74,385, dated February 11, 1868.

IMPROVED TUBE-HOLE CUTTER.

The Schedule referred to in these Letters Patent and making part of the same.

TO ALL WHOM IT MAY CONCERN:

Be it known that I, CHARLES H. LAVIS, of the city and county of Philadelphia, and State of Pennsylvania, have invented a new and improved Boring-Bar or Tube-Sheet Borer; and I do hereby declare that the following is a full, clear, and exact description of the same, reference being had to the accompanying drawing, and to the letters of reference marked thereon, making part of this specification, in which--

Figure 1 is an elevation,

Figure 2 is a sectional elevation,

Figure 3 is an end view of the shank, and

Figure 4 shows a sheet partly grooved or cut.

Similar letters refer to similar parts in the several views.

A is a shank, which is forged with a swell or large portion, B, on its end. It has longitudinal grooves, *a a a*, as shown in fig. 3, formed in its outer surface, corresponding to the number of cutters, *b b b*, which take into these grooves. Any number of cutters can be employed, four being shown in this instance, their cutting parts being curved to suit the circle they work in. A ring, C, is slipped over the cutters to hold them firmly in place, and adjust them so that all the points may work at once. This ring has set-screws, *d d d*, for each cutter, and one of the cutters may be made to countersink or give a bevel to the hole or flue-opening at the same time that it is bored, or an additional cutter, solely for the purpose of countersinking, may be employed. A socket, *e*, is formed in the shank A, commencing at its lower or enlarged end. A centre, D, takes into it. A spiral or other spring, E, is also inserted into the said opening or socket, above the centre D, its ends bearing against the top of the centre and the top of the socket. *f* is a slot, formed either through or partly through the shank A. A screw or pin, *g*, which keeps the centre D from either dropping or being forced out of the socket by the spring F, by being fixed to the said centre, moves up and down in the said slot with the centre, and is so adjusted relative to it, that when the centre is at its lowest point, the pin is locked or held in the bottom end of the slot.

To operate my boring-bar or tube-hole cutter for boilers, &c., the sheet to be bored having been previously marked off and centre punched, is placed on the table of a drill-press, and the shank, A, inserted into the spindle of the same, which is then screwed down until the point of the centre D takes into either of the centre punch-marks. On the press being started and the spindle fed down, the cutters *b* feed into the sheet, and remove a ring of metal corresponding to the width of the cutters. It will be observed that as the cutters feed down, the centre, D, moves up the socket *e* in the shank, compressing the spring E, and when the cutters have performed their work, the spring reacts and forces the centre down, thereby removing the washer or circular flat plate of metal remaining.

The advantages of this tool for cutting out the tube-holes in the flue-sheets of boilers are, that it works fast and with great certainty of execution, and the cutters, which often break even with the greatest care, can be easily dressed when broken, in a short time, and at a slight cost, thus making its use economical both in point of execution and cost of repair.

What I claim as my invention, and desire to secure by Letters Patent, is--

The tool, as a whole, when its several parts are combined, constructed, and arranged as set forth.

In testimony whereof, I hereunto sign my name to this specification, in presence of two subscribing witnesses.

CHARLES H. LAVIS.
